UNITED STATES PATENT OFFICE.

MATTHEW MAYER, OF MANSFIELD, OHIO, ASSIGNOR TO CHARLES M. WALTER.

BOWDEN CONTROLLING MECHANISM.

Application filed May 2, 1924. Serial No. 710,686.

To all whom it may concern:

Be it known that I, MATTHEW MAYER, a citizen of the United States, residing at Mansfield, State of Ohio, have invented certain new and useful Improvements in Bowden Controlling Mechanisms, of which the following is a specification.

My invention relates to Bowden controlling mechanisms, and more particularly relates to mechanisms employing a Bowden wire for transmitting motion longitudinally of the wire from a manually controlled element to an adjustable mechanism element.

More particularly my invention relates to such a controlling mechanism wherein the manually operable element will be retained in any desired intermediate or extreme mechanism adjusting position.

An object of the present invention is to provide a mechanism of the above type which will be inexpensive to manufacture and which will be positively retained in a given adjustment, and which can be easily re-adjusted.

Other objects of my invention and the invention itself will be apparent from the description of specific embodiments of my invention shown in the drawings accompanying this specification.

Referring to the drawings—

Fig. 1 shows a plan view of a mechanism embodying my invention,

Fig. 2 shows a section on line 2—2 of Fig. 1,

Fig. 3 shows a longitudinal medial sectional view of the embodiment illustrated in Fig. 1,

Fig. 4 shows a plan view of a second embodiment of my invention,

Fig. 5 shows a section on the line 5—5 of Fig. 4,

Fig. 6 shows a longitudinal medial section of the embodiment shown in Fig. 4,

Fig. 7 shows a longitudinal medial section of the manually displacing plunger element illustrated in Fig. 6, together with the Bowden wire connected thereto and comprising adjustment retaining means.

Referring now to the figures in all of which like parts are designated by like reference characters and particularly referring to that embodiment first shown in Figs. 1 to 3 inclusive, at 1 I show a tubular frame member having an outwardly extending angular flange 2 forming a face plate for the frame and having a spiral groove 3 formed on its interior cylindrical surface, the

groove 3 extending from the top of the member 1 and preferably extending adjacent to the end thereof. The lower end of the tubular element 1 is preferably externally threaded as shown at 4 for the reception of a retaining nut 5, said nut having an inwardly extending flanged portion 6 so as to give the nut 5 the character of a perforated cap nut. Through the perforation 7 in the nut 5 extends the Bowden wire directing and protecting tube 8, said tube having an angularly outwardly inclined flanged head 9, said head 9 being clamped under the inwardly extending flange 6 of the nut 5 which presses it against the end of the tubular frame member 1, and therefore securely holds, by its flanged head, the Bowden wire enclosing tube 8.

Preferably I may employ a concave perforated washer 10 between the flanged head 9 of the tube 8 at the end 11 of the tubular frame member 1, the Bowden wire 12 passing through the perforations in such concave washer.

Disposed within the tubular member 1, I provide a Bowden wire operating piston member 13 to the end of which is secured the Bowden wire 12. Preferably the end of the rod 13 is reduced, flattened and pierced at 14 to receive the looped end 15 of the Bowden wire. The rod 13 has an enlarged head 16 suitably formed as shown at 17 so as to be readily grasped by the hand of the operator of the mechanism, and providing a shoulder at 18 adapted to contact with the upper end 19 of the tube 1 so as to limit the inward movement of the rod 13 when telescoped within the tube 1 as shown in the drawings.

A recess 20 is provided in the rod 13 and disposed within this recess a ball 21 spring pressed by a spring 22 against inwardly converging walls 23 of the recess which would prevent its removal therefrom. The ball 21, however, has a portion of its outer surface adapted to project beyond the plane of the top of the recess and into the spiral groove convolutions 3 whenever the rod 13 is reciprocated within the tube 1 so as to make the ball 21 index with such groove convolutions. When so positioned, the spring pressed ball 21 entering a convolution of the spiral groove 3 will serve to resiliently hold the reciprocable rod in a given set position from which it will not be displaced by ordinary causes such as vibration, but can only be moved therefrom by a forcible operation

of the rod 13 such as by the operator's grasping the handle 17 and moving it longitudinally of the apparatus.

The recess 20 is provided by drilling from 5 one side of the rod to the interior thereof thereafter placing the spiral spring 22 in the recess and the ball 21 on top of the spring 22 and then by peening over the edges of the cylindrical recess, or by otherwise 10 forming the inwardly extending upper walls thereof.

The flanged head 2 for the tube 1 is suitably perforated at 24 and 25 for the reception of screws 26 which permit the mechanism 15 to be secured to a fixture such as the dashboard of an automobile indicated herein at 27, said dash being perforated at 28 so as to receive the shank of the tubular element 1.

20 Referring now to the embodiments shown in Figs. 4 to 7 inclusive, generally the structure is the same except that in this embodiment I may thread the exterior surface of the tube 1 as shown at 38 and provide a 25 securing nut 29 and washer 30 to take the place of the screws 26 for the purpose of securing the apparatus to the dash-board 27. In such a case I may replace the flanged head 2 by a nut 28 thereby permitting the 30 making of the tube 1 in an automatic screw machine which cannot well be done with the embodiment illustrated in the foregoing figures without undue waste of metal. In this embodiment, likewise, the interior wall 35 of the tube 1 is provided with a spiral groove, but instead of the spring pressed ball 21 coming to rest within the said groove for adjustment retaining purposes as before mentioned, I herein extend the end of the 40 Bowden wire 12 through the opening 14 of the flattened end of the rod 13 and pass it over the rod 13 as shown particularly in Fig. 7, the extended end 30 of the wire 12 resting within a longitudinal groove 31 of 45 the rod 13, there being an intermediate portion of the wire extension 40 as shown at 32 which is humped rather abruptly outwardly from the rod 13, and the spring tension of the wire end 30 permits this humped 50 portion 32 to yield resiliently when the rod 13 is placed within the tube 1, but at the same time causes it to press firmly into any of the groove convolutions 3 with which it may at the time be indexed depending on 55 the particular longitudinal adjustment of the rod 13 with respect to the tube 1.

Having thus described my invention in

two embodiments, I am aware that numerous and extensive departures may be made from the embodiments herein illustrated and described, but without departing from the spirit of my invention.

I claim:

1. In a Bowden wire controlling mechanism, the combination with a tubular frame member of a reciprocable rod adapted for insertion within the frame member, of a Bowden wire secured to one end of the rod member and a manually operable handle portion for the other end of the rod member, the interior wall of the tubular frame being spirally grooved and a spring pressed element carried on the rod within the tube and adapted to have a portion projected within the convolutions of the spiral groove of the tube's inner wall.

2. In a Bowden wire controlling mechanism, the combination with a tubular frame member of a reciprocable rod adapted for insertion within the frame member, of a Bowden wire secured to one end of the rod member and a manually operable handle portion for the other end of the rod member, the interior wall of the tubular frame being spirally grooved and a spring pressed element carried on the rod within the tube and adapted to have a portion projected within the convolutions of the spiral groove of the tube's inner wall, said spring pressed element comprising a ball, said ball being positioned within a recess in the said rod and having a portion of the ball spring pressed into any of said convolutions which by movement of the rod, said ball may be brought into indexed relationship.

3. In a Bowden wire controlling mechanism, the combination with a tubular frame member of a reciprocable rod adapted for insertion within the frame member, of a Bowden wire secured to one end of the rod member and a manually operable handle portion for the other end of the rod member, the interior wall of the tubular frame being spirally grooved and a spring pressed element carried on the rod within the tube and adapted to have a portion projected within the convolutions of the spiral groove of the tube's inner wall, said spring pressed means comprising an extension of the Bowden wire.

In testimony whereof I hereunto affix my signature this 22 day of April, 1924.

MATTHEW MAYER.
